UNITED STATES PATENT OFFICE.

MOSES G. HODGES AND ADOLPH SCHILLINGER, OF TULSA, OKLAHOMA.

PRESSURE DEVICE.

Application filed November 22, 1926. Serial No. 149,964.

Our invention relates to pressing devices and especially to devices of that type which are employed for imparting or restoring a smooth and even surface to woven fabrics.

5 The object of our invention is to provide a device of simple and durable construction having suitable clamping and pressure-applying means so as to constitute a device which is easy and efficient of operation in its employment for the purpose of pressing wearing apparel such as neckties or the like that may be operated without hazard to the coloring elements of the apparel, and that may be operated without the necessity of a supply of 10 steam or similar heating elements.

In the present practice of pressing certain articles of wearing apparel such as neckties, a device employing heat is used, whereby the heat is applied together with pressure for 20 the purpose of restoring the articles to their original flat and shapely appearance. Such articles are usually provided with colorful designs printed or woven into the same and produced by coloring matter having chemical 25 properties. The colors are subject to diffusion by the application of intense heat and by the application of heated moisture or moisture in association with heat. It is apparent, therefore, that the employment of 30 heat for the aforementioned purpose is objectionable, since it may cause fading and discoloration of the article to which it is applied.

Our device provides for pressure applying 35 plates having moisture absorbing means whereby the employment of heat as at present used for drying purposes is eliminated, and the shapeliness of the articles is restored and their decorative designs remain unimpaired.

40 In accomplishing this object we have provided improved details of structure, the preferred forms of which are illustrated in the accompanying drawings wherein:

Fig. 1 is a perspective view of the device 45 as when in use.

Fig. 2 is a perspective view of the device as opened for receiving or removing an article therefrom.

Fig. 3 is a sectional view taken on the line 50 3—3, Fig. 4.

Fig. 4 is a sectional view partly broken away, taken on the line 4—4, Fig. 3.

Fig. 5 is a detail perspective view of the shaping tongue.

55 Fig. 6 is a detail perspective view of the clamp pivot plate.

Fig. 7 is a detail perspective view of the clamping lever.

Referring in detail to the drawings:

1 designates a necktie such as commonly used, having the longitudinal opening or channel 2 between the layers of material of the tie and extending the length of the tie. A thin strip-like element 3 is provided preferably of metal and constituting a tongue 60 having the same general tapering shape as a necktie, the tongue 3 comprising tapering sections 4 and 5, the two sections being joined by a hinge joint which is thin and of leather or other flexible material. The hinge 6 is 65 riveted to the tapering sections 4 and 5 of which the tongue is composed in such a way that the tongue is adapted for folding upon itself when not in use. The tongue is designed for insertion into the channel or opening 2 of the necktie, and for extension therein until the advancing extremity of the tongue reaches a point substantially midway of the length of the necktie channel, whereby the said tongue is positioned in the parts of 70 the necktie that are exposed and wrinkled in the wearing of the same. The tongue so positioned, its planes respectively parallel with the corresponding planes of the necktie, 75 serves to hold the tie in a desired shape 80 preparatory to its application to a pressing device 7.

The pressing device 7 consists of the upper and lower pressure plates 8 and 9, which are tapered so as to conform to the shape of a tie 90 and are of such length that the pair of plates are adapted to cover that said portion of the tie which is subjected to wrinkling when in use. The inner surfaces of the pressure plates are lined with a soft absorbent material such as the felt 10 so that the plates may be tightly and yieldingly clamped together.

Feet 11 of soft material such as rubber are secured to the bottom side and at the corners 100 of the lower pressure plate 9 so that the device may be placed upon a finished wood surface as that of a dresser without scratching or otherwise marring such surface.

A U-shaped clamp 12 is secured to the lower pressure plate 9 by means of the screws 13, and has inturned hooks 14 to engage a clamp lever pivot plate 15 by means of the ears 16 with which said plate 15 is provided. Upstanding lugs 17 are provided on the pivot plate 15 and are spaced so as to receive the cam-like hub portion 18 of the clamp lever 105 110

19 which is mounted for pivotal movement on the pivot pin 20 retained by said lugs. The hub portion 18 of the clamp lever is provided with an offset aperture 21, by reason of which 5 the clamp lever is eccentrically pivoted by the pin on the lugs and in relation to the lower pressure plate. An opening 22 is provided in the clamp lever pivot plate 15, wherethrough the eccentrically pivoted hub 10 portion 18 of the clamp lever 19 is permitted to project into contact with the upper surface of lower pressure plate 9.

Assuming the device to be constructed and assembled as described, its operation is as 15 follows:

In order to insert an article in the device for pressing, the clamping lever 19 is moved to the position as shown in dotted lines in Fig. 4, thereby releasing the pressure from 20 the plate 8 in its contact with the lower plate 9 and also releasing the upward pressure of the pivot plate 15 in its contact with the in-turned hooks 14 of the U-shaped member 12. The clamping device (Fig. 2) is then removed and the pressure plate 8 withdrawn. 25 A tie or like article is then placed on the felt surface of the plate 10, and the plate 8 and the clamping device are replaced in operative position. The lever 19 is moved from the 30 position as shown in the dotted lines in Fig. 4 to that shown in full lines causing the eccentrically pivoted hub 18 to engage the upper surface of the plate 9, pressing same downwardly and thus exerting pressure on 35 the article positioned between the plates. By having the plates lined with a soft absorbent material such as felt, the article which is placed in the device in a dampened condition will be deprived of its moisture during the 40 period it is held under pressure and when removed from the device it will have been restored to a dry, flat and shapely condition.

The metal strip or tongue is an important factor in the result, since it stabilizes the 45 planes into which the fabric of the tie is to be pressed, and it provides a smooth hard surface whereby an ironing out and smooth-

ing effect is secured on a wrinkled area of relatively thin material subjected to the operation of the device.

What we claim and desire to secure by Letters Patent is:

1. In a necktie pressing device, mated upper and lower pressing boards, a clamp fixed to the lower board and having clamping ears, a clamp lever plate having extensions for movable engagement with the ears of the clamp, a lever arm eccentrically mounted on the clamp lever plate, the plate having an opening, the lever arm having a portion projecting through said opening to bear against the upper board and press one board against the other on operation of the clamp lever, and a hinged strap adapted to shape the necktie and promote the smooth pressing thereof. 60

2. In a clamping device for mated upper and lower pressing boards, an apertured clamp lever plate, a clamp attached to the lower board and having clamping ears for receiving the plate when the plate is elevated by a lever, and a clamp lever eccentrically mounted on said plate, and having a portion movable through the aperture of the lever plate for urging the upper board towards the 70 lower board against the resistance of the clamp. 75

3. In a clamping device for mated upper and lower pressing boards, a clamp attached to the lower board, and having clamping ears, a movable clamp lever plate having extensions adapted for positioning for engagement with the ears of the clamp upon positioning of the plate on the upper board, a lever arm pivotally mounted on the clamping 85 plate having a cam member, the plate having an opening, the lever being adapted to project the cam member through said opening to press one board against the other on 90 operation of the lever arm.

In testimony whereof we affix our signatures.

MOSES G. HODGES.
ADOLPH SCHILLINGER.
